F. MANKEY.

PANEL.

No. 17,112.

Patented Feb. 15, 1887

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,112, dated February 15, 1887.

Application filed December 30, 1886. Serial No. 923,049. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design consists in the raised parallelogram A and the two smaller rectangular elevations, B and C, all having flat surfaces and rounded edges. Parallel to the sides of parallelogram A are rounded beads D E F G. Between said parallelogram and said beads is a channel, H. Between the extremities of beads D E F G are rounded elevations P. I J K L M are beads having rounded edges and appearing parallel to the sides of the elevations B C. The bead I is between said eleva-

tions. Between each elevation B and C and adjacent encompassing beads is a channel, N. Between the proximate ends of the beads I J K is a rounded elevation, O. Between the proximate ends of the beads K J and M L are rounded elevations Q. Between the elevations P, G, and O and the ends of the adjacent beads are channels, as R.

I claim—

The design for a panel, substantially as herein shown and described, which consists in the raised parallelogram A and the two rectangular elevations B C, having rounded edges, rounded beads D E F G I J K L M, rounded elevations P Q O, and channels H N R.

FREDERICK MANKEY.
